(57) **CLAIM**

The ornamental design for an aviation wheel chock as shown and described.

DESCRIPTION

FIG. 1 is an elevated perspective view of a first embodiment of our new design of an aviation wheel chock;

FIG. 2 is an elevated reverse perspective view thereof;

FIG. 3 is a bottom perspective view thereof;

FIG. 4 is a reverse bottom perspective view thereof;

FIG. 5 is a front elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is an elevated perspective view of a second embodiment of our new design of an aviation wheel chock;

FIG. 11 is an elevated reverse perspective view thereof;

FIG. 12 is a bottom perspective view thereof;

FIG. 13 is a reverse bottom perspective view thereof;

FIG. 14 is a front elevation view thereof;

FIG. 15 is a right side elevation view thereof;

FIG. 16 is a left side elevation view thereof;

FIG. 17 is a top plan view thereof; and,

FIG. 18 is a bottom plan view thereof.

The broken lines depict portions of the aviation wheel chock that form no part of the claimed design.

1 Claim, 16 Drawing Sheets
